REGENERATIVE COMPOUND COKE-OVENS

Wilhelm Mueller, Gleiwitz, Germany

Application December 31, 1932, Serial No. 649,720
In Great Britain March 1, 1932

16 Claims. (Cl. 202—144)

The present invention relates to a regenerative compound coke-oven battery of the kind in which a number of coking chambers are arranged in a row, being separated one from another by heating walls each of which contains a single row of vertical flues in which an air/gas mixture is burned for heating the coking chambers and in which a set of regenerators is arranged under each coking chamber in the oven structure, each such set consisting in general of two groups one of which is arranged for pre-heating gas or air and the other for heating air only, it being understood that a single regenerator extending the whole length of the overlying coking chamber may be used instead of a group of regenerators.

The invention has for an object to provide a compound coke oven battery with a highly efficient system of combustion in the heating flues of the chamber walls, to the end, that the principles of "multi-stage combustion" or "recirculation of waste gases" or a combination of these principles may be utilized in a coking retort oven, whether coke-oven gas be employed as the oven fuel, or a weak gas, such as producer gas or blast furnace gas.

Further, the two gases may be burned concurrently in which case the weak gas operates to dilute the coke-oven gas. The invention retains, with all of its advantages, the regenerative system of conserving the waste heat from the flues and utilizing such waste heat for pre-heating the weak fuel gas as well as the air for combustion.

The invention combines the regenerative system with its periodic reversal of flow, in such a way, that in the novel flue system the flame is maintained constantly in all the flues of each heating wall, regardless of whether the flue be the coke-oven gas distilled from the coal coked in the oven chambers, or the fuel be an alternatively employed weak-gas, such as producer gas, or blast furnace gas, with the result that uniformity in temperature of the heating walls is promoted, extreme temperature variations are eliminated, and the charges of coal within the several coking chambers are subjected constantly throughout their entire extent to the high temperature of burning flames, and no retardation of the carbonizing or coking process can result from the reversal of flow through the regenerators.

By the invention, the efficiency of a coke-oven is greatly promoted, notwithstanding the fuel employed, the carbonizing process is carried on

most evenly, with greater facility and in a shorter time than has been heretofore possible, on account that temperature fluctuations are practically eliminated through the novel combination of the heating arrangement of the oven 5 chambers.

In certain known ovens of the general kind referred to the delivery of air and gas from the regenerators to the heating flues was by means of intermediate long transfer channels. This 10 arrangement besides requiring undesirable complication in the structure of the oven is disadvantageous in that the preheated gas or/and air is pressed together again and has subsequently to be redistributed to the various heat- 15 ing flues and whereby unevenness of heating is liable to be set up. The present invention provides for the elimination of the above named disadvantages.

The invention consists in the novel features, 20 methods, combinations and constructions herein illustrated, described and claimed.

In describing the invention reference is had to the accompanying drawings, in which like reference characters designate corresponding 25 parts and which illustrate by way of example typical embodiments of the invention including various modifications of detail.

In the drawings:—

longitudinally of the oven walls and having flue connections as in Fig. 2.

In the illustrations generally K is the oven chamber and W the heating wall. 1 and 1^a are the gas distribution channels and 2 and 2^a are the air distribution channels which are arranged under the oven chambers in the longitudinal direction of the latter. These channels 1, 2 and 1^a, 2^a are openly connected in an upward direction 10 with the gas regenerators 3 and 3^a and the air regenerators 4 and 4^a. The regenerators are arranged longitudinally under each oven chamber and consist either, as in Figs. 5 and 6, of a larger central gas regenerator 3, 3^a and two lateral air regenerators 4, 4^a arranged at the side of the former, or as in Figs. 7 and 8, only of one gas regenerator 3 (or 3^a) and one air regenerator 4, 4^a which are similar and occupy the whole length of the chamber. In Figs. 9, 10 and 11 is illustrated an alternative regenerator arrangement of which a detailed description will hereinafter be found.

The coal to be coked is charged into the several coking chambers or ovens K through charging holes K¹ positioned directly above the ovens or chambers K as shown in Fig. 12. These charging holes K¹ are equipped with the usual removable covers K² which are removed when charging any of the several ovens and placed in position to close the tops of the ovens during the entire coking operation.

The gases of distillation pass from the tops of the several coking chambers K through the usual gas outlets K³ and communicably connected ascension pipes K⁴ (Figs. 5, 10 and 11) into the usual gas collecting main which carries the distillation productions to the by-product recovery apparatus.

Heat for coking the charges of coal in the several ovens or chambers K is derived from the heating walls W, which, as before mentioned, extend crosswise of the battery at the sides of the coking chambers. The construction and the functioning of these heating walls constitute important features of the present invention.

Each regenerator is a chamber containing open brickwork, commonly called checkerwork. These regenerators in alternation are heated by the hot combustion products that draw off from the heating or combustion flues (7, 8) hereinafter further described and then impart such heat to the medium that they feed into these heating flues.

These regenerators are connected directly by transfer passages 13, 14 (or 13^a, 14^a) or/and 15, 16 (or 15^a, 16^a) which partly cross each other and rise obliquely, with the lower ends of the heating flues 7, 8 or/and of two vertical ducts 11, 12 (or 11^a, 12^a) respectively which latter are provided in the binder-bricks of the chamber walls, one of said ducts being connected with the gas regenerator 3, (or 3^a), while the other is connected with the air regenerator 4 (or 4^a). As will be seen from the drawings the passages 13, 14, 13^a, 14^a lead from the lower ends of flues 7, 8 and the passages 15, 16 from the lower ends of ducts 11, 12, 11^a, 12^a into regenerators 3, 4, 3^a, 4^a. The ducts 11, 12, 11^a, 12^a have, at their lower end, and if desired also at a higher level, ports 9 which open laterally into the heating flues 7, 8. All the flues 7, 8 and vertical ducts 11, 12, 11^a, 12^a open at the top into an upper horizontal interconnecting passage 10.

In the oven of Figs. 1, 3 and 5, the two ducts 11, 12 of one row of bricks are connected by passages 15, 16 to the left with the regenerators 3, 4 respec-

tively while the two ducts 11^a, 12^a of the next row are connected by passages 15^a, 16^a to the right at the bottom with the regenerators 3^a, 4^a respectively.

In the oven illustrated in Figs. 2, 4 and 6 the 5 passages 13, 14 opening out of the lower ends of the heating flues 7 of any one heating wall instead of sloping alternately to left and right for connection with the regenerators 3, 4 and 3^a, 4^a respectively are arranged to slope all in the same 10 direction for connection with the regenerators 3, 4 and similarly with the passages 15, 16 which all slope in the same direction from the lower ends of the vertical ducts 11, 12 of any one heating wall for connection with the regenerators 3^a, 4^a. In 15 other words the regenerators 3, 4 are connected by passages 13, 14 which slope to right and left, with the lower ends of the heating flues 7 in the heating walls on both sides of the coking chamber placed above the regenerators 3, 4; and in like 20 manner the next pair of regenerators 3^a, 4^a are connected by passages 15, 16 sloping to right and left, with the lower ends of the vertical ducts 11, 12 in both the adjacent heating walls.

In Figs. 7, 8 the arrangement of coking chambers K, flues 7, 8 and vertical ducts is exactly the same as the respective parts in Figs. 5 and 6, the only difference in the structure being with regard to the regenerators 4, 3, 4^a, 3 which are arranged in pairs comprising one gas regenerator 3 or 3^a and one air regenerator 4 or 4^a, instead of groups of three as shown in Figs. 5 and 6 and occupy as before the entire length of the chamber. The arrangement of the oblique transfer ducts 13, 14, 15 and 16 etc. is also substantially the same as before, being suitably modified for connection with groups of two regenerators instead of groups of three. In this case the inner oblique transfer passages 15, 15^a (in Fig. 7) and 13, 15 (in Fig. 8) from each regenerator pair are 40 arranged to cross one another.

The immediate connection with the regenerators of the heating flues 7, 8 or/and of the two brick ducts 11 and 12 in conjunction with the side ports 9 hereinafter described, make it possible, as was not possible hitherto, to convey pre-heated weak gas and air from the regenerators at several heights into each heating flue and therefore to provide either multi-stage combustion or/and a recirculation of combustion products in 50 each pair of heating flues in the oven walls.

For the purpose of conveying weak gas and air, there are provided in the substructure arranged under the ovens, special distribution conduits S and L with perpendicular nozzles d and h (see 55 Figs. 5, 6, 7 and 8) which convey the gas or the air under a moderate pressure into the channels 1 and 2 or 1^a and 2^a and from there to the regenerators 3 and 4 or 3^a and 4^a.

For the purpose of conveying rich gas, the ovens 60 are provided with conduits R having vertical nozzles 5, which are also arranged in the substructure under the oven, or with horizontal channels 6 having corresponding nozzles connecting them with each heating flue 7, which are arranged 65 in the brickwork. In the same way rich gas can be conveyed to each of the heating flues 7 and 8 from the top through the channel 7 and the nozzles 7^a.

For working the oven according to Figs. 1, 3 70 and 5 or Fig. 7 with weak gas, the latter is conveyed through the conduit S and the nozzles d to the channels 1^a. The air is conveyed in a similar way through the conduit L and the nozzles h into the channels 2^a.

From channels 1^a and 2^a the gas and the air rise into the regenerators 3^a and 4^a (Fig. 5 or 7) where they are heated to high temperature, whereupon they flow through the passages 15^a and 16^a to the 5 brick ducts 11^a and 12^a. From there the gas and the air enter the heating flues 8 through ports 9 at different heights, where they burn and flow upwards. The flames enter through the opening 10 into the adjacent flue 7, flow through the flue in 10 a downward direction and through the lateral ports 9 are diluted by recirculation of the combustion products, the ducts 11, 12 and passages 15, 16 serving to carry off the waste gases into the regenerators 3 and 4. The waste heat flows 15 through the channels 1 and 2 to the main waste heat channel and through the chimney into the open. If the gas valves, air valves and waste heat valves are reversed, gas, air and flames in the heating flues and the waste heat in the regenerators, all flow in the opposite direction and the 20 ports 9 by supplying flames at a number of levels give multi-stage combustion.

It will thus be seen that the flues 7, 8 operate in alternation as upcast and downcast flues and 25 that the alternate pairs of vertical ducts 11^a, 12^a and 11, 12 act respectively for supplying fresh heated gas and air and withdrawing the waste gases, the direction of flow being indicated by the arrows in Fig. 1.

30 The heating walls of the oven, according to Figs. 2, 4 and 6 or Fig. 8 are treated with weak gas in the same way as is described above but with the difference that the gas and air are, in the one instance, made to enter at the foot of 35 the heating flues 7 from the regenerators 3 and 4 through the passages 13 and 14, when the waste heat will flow off on top through the brick ducts 11 and 12 and pass to the other regenerators 3^a, 4^a, while, after the change over, the gas and 40 the air will flow from the regenerators 3^a and 4^a and the passages 15 and 16 through the brick ducts 11 and 12 from the top into the heating flues 7, and the waste heat will then flow off to the regenerators 3 and 4 through the passages 13 45 and 14. With regenerators 3, 4 acting to supply heat to the gas and air all the flues work as upcast flues and the ports 9 operate to produce recirculation of waste gases. On reversal of the flow all flues become downcast and ports 9 give 50 multi-stage combustion by supplying flames at a number of different levels.

If the oven, according to any of Figs. 1 to 8, is worked only with rich gas, then the weak gas conduits S and d which open at the bottom into 55 the regenerators, are shut in the already known way, whereupon the regenerators 3 and 4 under one oven chamber work alternately only with air, while the regenerators 3^a and 4^a under the adjacent chamber work with waste heat, this being 60 reversed after the change over. The rich gas is then conveyed to the separate heating flues from below either through the nozzles 5 or the channels 6, while the rich gas enters the heating flues from the top through the channels 17 and the nozzles 17^a.

65 Figs. 3 and 4 illustrate the parts of the heating walls W for the oven chambers, which contain also the two vertical brick ducts 11 and 12 between the heating flues 7 and 8. 70 These heating walls W are constructed in such a way that there is, so to speak, an elastic connection between the binding bricks and the stretchers, in order to obtain a reliable flow of gas and air from the regenerators 3 and 3^a and 4 75 and 4^a to the lateral and multi-stage outlet ports

9 of the brick ducts 11 and 12 and to the heating flues 7 and 8. The construction of the brickbond is suitably formed by alternation horizontally and vertically of one whole binder-brick 20 without head, and with two half-bricks 21 with one head each, (for which see also Fig. 6); and with stretcher-bricks 22 forming the sides of the wall, which are provided with equal notches 23 on either edge to key with the projecting heads of the binder-bricks, the binder-bricks being provided, if required, with round or otherwise suitably formed holes to build up the two vertical ducts 11 and 12 as has been stated before.

The general lay-out of the oven is shown in Fig. 12 which refers particularly to the arrangement illustrated in Fig. 2 or Fig. 6. The lay-outs of the arrangements according to Figs. 1 and 5 are similar, the differences being as hereinbefore fully set forth in the description relating to Figs. 1 and 5.

In the ovens of Figs. 9, 10 and 11 a row of small separate regenerators as 3, 4, 3^a, 4^a are arranged underneath each coking chamber, alternate rows being respectively traversed by fresh gas or/and air and by waste gases and alternate regenerators of the row in use for heating being traversed respectively by air and gas when the oven is being worked with weak gas requiring preheating. Thus in Figs. 9 and 10 weak gas is supplied 30 through a channel 1 to regenerators 3 and air through a channel 2 to regenerators 4 alternating in the same row with regenerators 3, the gas passing from the regenerators 3 through passages 13 and the air from regenerators 4 through passages 14 to the lower ends of the heating flues 7 35 the waste gases being withdrawn at the top and led down the vertical ducts 11, 12 into the regenerators 3^a, 4^a of the adjacent row.

On reversal the gas passes through channel 1^a, regenerators 3^a, passages 15 and vertical ducts 40 11 and air through channel 2^a, regenerators 4^a, passages 16 and vertical ducts 12, the gas and air mixing in the upper connecting passages 10 and the flames passing down the flues 7, while the waste gases are withdrawn through the regenerators 3, 4 and channels 1, 2.

As in the previous examples, ports or openings 50 9 give communication between the flues 7 and vertical ducts 11, 12, whereby multi-stage combustion and/or recirculation is promoted.

Rich gas may be supplied either from below by means of upright nozzles 5 or from above by means of horizontal channels 17 and downwardly directed nozzles 17^a.

In the modification illustrated in Fig. 11, alternate flues 7, 8 are respectively connected by means of passages 13, 14 with the gas and air regenerators 3, 4 and by passages 13^a, 14^a with the waste gas regenerators 3^a, 4^a, so that the flames pass up flues 7 and down flues 8. Each partition between 60 the flues 7, 8 contains a pair of vertical ducts 11, 12, which are alternately connected with gas and air regenerators 3, 4 and the adjoining waste heat regenerators 3^a, 4^a by means of the passages 15, 16 and 15^a, 16^a.

As before a number of side ports or openings 8 connect the flues 7, 8 with the ducts 11, 12 for the promotion of multi-stage combustion in the upcast flues 7 and recirculating the combustion products in the downcast flues 8.

70 The technical advantage of the invention consists in that, in the case of coke ovens with multi-stage combustion or/and recirculation of gases, the lower ends of the heating flues, as also of the two vertical ducts which are arranged in the 75

brickwork between the heating flues, are in immediate connection in a downward direction with the gas and air regenerators 3 and 4 and 3^a and 4^a respectively, by short passages which partly cross each other. In comparison with the system of arranging in these ovens, between the heating walls and the regenerators, long sole or transfer channels in a horizontal direction, the present invention is a simplification of the construction, and furthermore ensures also an even distribution of gas and air throughout the whole length of the oven chamber, because the heating flues of the walls are at each place directly connected with the regenerators.

15 15 What I claim is:—

1. A regenerative coke-oven battery including a series of alternate horizontal coking chambers and heating walls therefor arranged side by side in a row having a single row of vertical heating flues arranged in each heating wall, and with a plurality of regenerators arranged beneath the coking chambers, the heating walls whereof are each constituted by bricks forming the sides of the wall, the said bricks being laid with their length 25 along the face of the wall and hereinafter referred to as stretcher bricks, and binder-bricks forming columnar partitions between the flues, each said partition having in vertical alternation a single binder-brick not extending to the outside of the wall, and a pair of half binder-bricks having heads extending to the outside of the wall between the stretcher-bricks, the stretcher and the binder-bricks being notched to key with one another, each of the said binder-bricks being 30 provided with holes suitably formed to build up two vertical ducts in each said columnar partition for directly connecting the upper ends of the heating flues with the regenerators beneath the oven chambers.

40 2. A heating wall for a regenerative coke-oven battery as claimed in claim 1, characterized by the alternation in the successive columnar partitions between the heating flues of said heating wall on any horizontal section through the wall 45 of single binder-bricks not extending to the outside of the wall with pairs of half binder-bricks having heads extending to the outside of the wall.

3. In a regenerative compound coke oven battery having a series of alternate horizontal coking chambers and heating walls therefor arranged side by side in a row, and regenerators arranged underneath each coking chamber, a single row of vertical heating flues and a horizontal channel interconnecting the upper ends of 55 said heating flues being arranged in each heating wall; means for elongating the flames of each heating flue said means serving during alternate periods between flow reversals to produce multistage combustion, i. e. supplying regeneratively 60 preheated air and optionally weak gas also at a plurality of levels within said heating flue, and the same said means serving during the intermediate periods between flow reversals to recirculate the products of combustion in said heating flue.

65 4. In a regenerative compound coke oven battery having a series of alternate horizontal coking chambers and heating walls therefor arranged side by side in a row, a set of regenerators arranged underneath each coking chamber, a single 70 row of vertical heating flues and a horizontal channel interconnecting the upper ends of said heating flues arranged in each heating wall, means for admitting air to all and fuel gas to some of the regenerators, means for withdrawing 75 waste gas from the regenerators, valve means for

operating the regenerator sets underlying alternate coking chambers of the row as heat receivers and as heat restorers respectively and for reversing the functions of regenerator sets, the combination of vertical ducts arranged in the 5 columnar partitions between the heating flues of each heating wall and opening into said horizontal channel, each cross partition having a pair of such vertical ducts, oblique ascending transfer passages issuing from the regenerators and 10 opening directly into the lower ends of said paired vertical ducts and ports leading out of one side of each heating flue near the bottom and also at one level at least below the top and communicating with both the vertical ducts adjacent to said 15 side of the heating flue, said ports serving (a) during alternate periods between flow reversals to introduce air and optionally fuel gas also from the heat restoring regenerators into the heating flues at more than one level to produce elongated 20 flames by multistage combustion and (b) during intermediate periods between flow reversals to recirculate combustion products within the heating flues and elongate the flames by dilution of the 25 burning gases.

5. In a regenerative compound coke oven battery having a series of alternate horizontal coking chambers and heating walls therefor arranged side by side in a row, a set of regenerators arranged underneath each coking chamber, a single row of vertical heating flues and a horizontal channel interconnecting the upper ends of said heating flues arranged in each heating wall, means for admitting air to all and fuel gas to some of the regenerators, means for withdrawing waste gas from the regenerators, valve means for operating the regenerator sets underlying alternate coking chambers of the row as heat receivers and as heat restorers respectively and for reversing the functions of regenerator sets, 30 the combination of vertical ducts arranged in columnar partitions between the heating flues of each heating wall and opening into said horizontal channel, each cross partition having a pair of such vertical ducts, oblique ascending 35 transfer passages issuing from the regenerators and opening directly into the lower ends of said paired vertical ducts, and ports leading out of one side of each heating flue near the bottom and also at one level at least below the top and 40 communicating with both the vertical ducts adjacent to said side of the heating flue; the pairs of vertical ducts of the same heating wall being connected alternately with the regenerator sets underlying the coking chambers on opposite sides 45 of said heating wall, the side ports of alternate heating flues of the same heating wall serving to introduce air and optionally fuel gas also from the heat restoring generators into said alternate heating flues at more than one level to produce 50 an elongated flame by multistage combustion and the side ports of the intermediate flues of said last-named heating wall serving to recirculate the products of combustion within said intermediate heating flues, thereby to elongate the 55 flames thereof by dilution of the burning gases.

6. In a regenerative compound coke oven battery having a series of alternate horizontal coking chambers and heating walls therefor arranged side by side in a row, a set of regenerators arranged underneath each coking chamber, a single row of vertical heating flues and a horizontal channel interconnecting the upper ends of said heating flues arranged in each heating 70 wall, means for admitting air to all and fuel gas 75

to some of the regenerators, means for withdrawing waste gas from the regenerators, valve means for operating the regenerator sets underlying alternate coking chambers of the row as heat receivers and as heat restorers respectively and for reversing the functions of regenerator sets; the combination of vertical ducts arranged in the columnar partitions between the heating flues of each heating wall and opening into the said horizontal channel, each cross partition having a pair of such vertical ducts, a set of oblique ascending transfer passages issuing from the regenerators and opening directly into the lower ends of said paired vertical ducts, another set of oblique ascending transfer passages issuing from the regenerators and opening directly into the lower ends of the heating flues and ports leading out of one side of each heating flue near the bottom and also at one level at least below the top and communicating with both the vertical ducts adjacent to said side of the heating flue; the vertical ducts of the same heating wall being connected by means of the first-named set of oblique transfer passages with the regenerators underlying the coking chamber on one side of said heating wall and the lower ends of the heating flues of the same and last-named heating wall being connected by means of the second-named set of oblique transfer passages with the regenerators underlying the coking chamber on the opposite side of said heating wall, said side ports serving during alternate periods between flow reversals to introduce air and optionally fuel gas also from the heat restoring regenerators into all the heating flues of the same heating wall at more than one level to produce elongated flames by multistage combustion and during the intermediate periods between flow reversals to recirculate the combustion products within all the heating flues of said last-named same heating wall, thereby to elongate the flames in said heating flues by dilution of the burning gases.

7. In a regenerative compound coke oven battery having a series of alternate horizontal coking chambers and heating walls therefor arranged side by side in a row, a pair of horizontally elongated regenerators oriented longitudinally of and located underneath each coking chamber, a single row of vertical heating flues and a horizontal channel interconnecting the upper ends of said heating flues arranged in each heating wall, means for admitting air to all and fuel gas to some of the regenerators, means for withdrawing waste gas from the regenerators, valve means for operating the regenerator sets underlying alternate coking chambers of the row as heat receivers and as heat restorers respectively and for reversing the functions of regenerator sets; the combination of vertical ducts arranged in the columnar partitions between the heating flues of each heating wall and opening into said horizontal channel, each cross partition having a pair of such vertical ducts, oblique ascending transfer passages issuing from the regenerators and opening directly into the lower ends of said paired vertical ducts and ports leading out of one side of each heating flue near the bottom and also at one level at least below the top and communicating with both the vertical ducts adjacent to said side of the heating flue, said ports serving (a) during alternate periods between flow reversals to introduce air and optionally fuel gas also from the heat restoring regenerators into the heating flues at more than one level to produce elongated flames by multistage combustion and (b) during intermediate periods between flow reversals to recirculate combustion products within the heating flues and elongate the flames by dilution of the burning gases.

and (b) during intermediate periods between flow reversals to recirculate combustion products within the heating flues and elongate the flames by dilution of the burning gases.

8. In a regenerative compound coke oven battery having a series of alternate horizontal coking chambers and heating walls therefor arranged side by side in a row, a set of three horizontally elongated regenerators oriented longitudinally of and located underneath each coking chamber, a single row of vertical heating flues and a horizontal channel interconnecting the upper ends of said heating flues arranged in each heating wall, means for admitting air to all regenerators and fuel gas to the central regenerator of each set of three, means for withdrawing waste gas from the regenerators, valve means for operating the regenerator sets underlying alternate coking chambers of the row as heat receivers and as heat restorers respectively and for reversing the functions of regenerator sets; the combination of vertical ducts arranged in the columnar partitions between the heating flues of each heating wall and opening into said horizontal channel, each cross partition having a pair of such vertical ducts, oblique ascending transfer passages issuing from the regenerators and opening directly into the lower ends of said paired vertical ducts and ports leading out of one side of each heating flue near the bottom and also at one level at least below the top and communicating with both the vertical ducts adjacent to said side of the heating flue, said ports serving (a) during alternate periods between flow reversals to introduce air and optionally fuel gas also from the heat restoring regenerators into the heating flues at more than one level to produce elongated flames by multistage combustion and (b) during intermediate periods between flow reversals to recirculate combustion products within the heating flues and elongate the flames by dilution of the burning gases.

9. In a regenerative compound coke oven battery having a series of alternate horizontal coking chambers and heating walls therefor arranged side by side in a row, a single row of regenerators arranged underneath each coking chamber, a single row of vertical heating flues and a horizontal channel interconnecting the upper ends of said heating flues arranged in each heating wall, the number of regenerators in each row being half the number of heating flues in each heating wall, means for admitting air to all and fuel gas to every second regenerator of each row, means for withdrawing waste gas from the regenerators, valve means for operating the regenerator sets underlying alternate coking chambers of the row as heat receivers and as heat restorers respectively and for reversing the functions of regenerator sets; the combination of vertical ducts arranged in the columnar partitions between the heating flues of each heating wall and opening into the said horizontal channel, each cross partition having a pair of such vertical ducts, oblique ascending transfer passages issuing from the regenerators and opening directly into the lower ends of said paired vertical ducts, and ports leading out of one side of each heating flue near the bottom and also at one level at least below the top and communicating with both the vertical ducts adjacent to said side of the heating flue; the pairs of vertical ducts of the same heating wall being connected alternately with the regenerator sets underlying the coking chambers on opposite sides of said heating wall, the side

ports of alternate heating flues of the same heating wall serving to introduce air and optionally fuel gas also from the heat restoring regenerators into said alternate heating flues at more than one level to produce elongated flames by multistage combustion and the side ports of the intermediate heating flues of said last-named heating wall serving to recirculate the products of combustion within said intermediate heating flues, thereby to elongate the flames thereof by dilution of the burning gases.

10. In a regenerative compound coke oven battery having a series of alternate horizontal coking chambers and heating walls therefor arranged side by side in a row, a single row of regenerators arranged underneath each coking chamber, a single row of vertical heating flues and a horizontal channel interconnecting the upper ends of said heating flues arranged in each heating wall, the number of regenerators in each row being equal to the number of heating flues in each heating wall, means for admitting air to all and fuel gas to every second regenerator of each row, means for withdrawing waste gas from the regenerators, valve means for operating the regenerator sets underlying alternate coking chambers of the row as heat receivers and as heat restorers respectively and for reversing the functions of regenerator sets; the combination of vertical ducts arranged in the columnar partitions between the heating flues of each heating wall and opening into the said horizontal channel, each cross partition having a pair of such vertical ducts, a set of oblique ascending transfer passages issuing from the regenerators and opening directly into the lower ends of said paired vertical ducts, another set of oblique ascending transfer passages issuing from the regenerators and opening directly into the lower ends of the heating flues and ports leading out of one side of each heating flue near the bottom and also at one level at least below the top and communicating with both the vertical ducts adjacent to said side of the heating flue; the vertical ducts of the same heating wall being connected by means of the first-named set of oblique transfer passages with the regenerators underlying the coking chamber on one side of said heating wall and the lower ends of the heating flues of the same and last-named heating wall being connected by means of the second-named set of oblique transfer passages with the regenerators underlying the coking chamber on the opposite side of said heating wall, said side ports serving during alternate periods between flow reversals to introduce air and optionally fuel gas also from the heating restoring regenerators into all the heating flues of the same heating wall at more than one level to produce elongated flames by multistage combustion and during the intermediate periods between flow reversals to recirculate the combustion products within all the heating flues of said last-named same heating wall, thereby to elongate the flames in said heating flues by dilution of the burning gases.

11. In a regenerative compound coke oven battery having a series of alternate horizontal coking chambers and heating walls therefor arranged side by side in a row, and regenerators arranged underneath each coking chamber, a single row of vertical heating flues and a horizontal channel interconnecting the upper ends of said heating flues being arranged in each heating wall, means for elongating the flames of each heating flue, said means serving during alternate periods be-

tween flow reversals to produce multistage combustion in odd-numbered heating flues of a row, i. e. supplying regeneratively preheated air and optionally weak gas also at a plurality of levels within said odd-numbered heating flues, and to 5 recirculate the products of combustion in even-numbered heating flues of the same row and the same said means serving during the intermediate periods between flow reversals to produce multistage combustion in the even-numbered heating 10 flues of said row and to recirculate the combustion products in the odd-numbered heating flues of said row.

12. In a regenerative compound coke oven battery having a series of alternate horizontal coking chambers and heating walls therefor arranged side by side in a row, and regenerators arranged underneath each coking chamber, a single row of vertical heating flues and a horizontal channel interconnecting the upper ends of said heating flues being arranged in each heating wall, means for elongating the flames of each heating flue, said means serving during alternate periods between flow reversals to produce multistage combustion, i. e. supplying regeneratively preheated air and 25 optionally weak gas also at a plurality of levels, within all the heating flues of a row and the same said means serving during the intermediate periods between flow reversals to recirculate the products of combustion in all the heating flues 30 of said row.

13. In a regenerative compound coke oven battery having a series of alternate horizontal coking chambers and heating walls therefor arranged side by side in a row, a set of regenerators arranged underneath each coking chamber, a single row of vertical heating flues and a horizontal channel interconnecting the upper ends of said heating flues arranged in each heating wall, means for admitting air to all and fuel gas to 40 some of the regenerators, means for withdrawing waste gas from the regenerators, valve means for operating the regenerator sets underlying alternate coking chambers of the row as heat receivers and as heat restorers respectively and for reversing the functions of regenerator sets, the combination of vertical ducts arranged in the columnar cross partitions between the heating flues of each heating wall and opening into said horizontal channel, each cross partition having a 45 pair of such vertical ducts, oblique ascending transfer passages issuing from the regenerators and opening directly into the lower ends of said paired vertical ducts and also into the lower ends of the heating flues and ports leading out of one 50 side of each heating flue near the bottom and also at one level at least below the top and communicating with both the vertical ducts adjacent to said side of the heating flue, said ports serving 55 (a) during alternate periods between flow reversals to introduce air and optionally fuel gas also from the heat restoring regenerators into the heating flues at more than one level to produce elongated flames by multistage combustion and (b) during intermediate periods between flow 60 reversals to recirculate combustion products within the heating flues and elongate the flames by dilution of the burning gases.

14. In a regenerative compound coke oven battery having a series of alternate horizontal coking chambers and heating walls therefor arranged side by side in a row, a pair of horizontally elongated regenerators oriented longitudinally of and located underneath each coking chamber, a single row of vertical heating flues and a horizontal 75

- channel interconnecting the upper ends of said heating flues arranged in each heating wall, means for admitting air to all and fuel gas to some of the regenerators, means for withdrawing waste gas from the regenerators, valve means for operating the regenerator sets underlying alternate coking chambers of the row as heat receivers and as heat restorers respectively and for reversing the functions of regenerator sets, the combination of vertical ducts arranged in the columnar partitions between the heating flues of each heating wall and opening into said horizontal channel, each cross partition having a pair of such vertical ducts, oblique ascending transfer passages issuing from the regenerators and opening directly into the lower ends of said paired vertical ducts and also into the lower ends of the heating flues and ports leading out of one side of each heating flue near the bottom and also at one level at least below the top and communicating with both the vertical ducts adjacent to said side of the heating flue, said ports serving (a) during alternate periods between flow reversals to introduce air and optionally fuel gas also from the heat restoring regenerators into the heating flues at more than one level to produce elongated flames by multistage combustion and (b) during intermediate periods between flow reversals to recirculate combustion products within the heating flues and elongate the flames by dilution of the burning gases.
15. In a regenerative compound coke oven battery having a series of alternate horizontal coking chambers and heating walls therefor arranged side by side in a row, a set of three horizontally elongated regenerators oriented longitudinally of and located underneath each coking chamber, a single row of vertical heating flues and a horizontal channel interconnecting the upper ends of said heating flues arranged in each heating wall, means for admitting air to all regenerators and fuel gas to the central regenerator of each set of three, means for withdrawing waste gas from the regenerators, valve means for operating the regenerator sets underlying alternate coking chambers of the row as heat receivers and as heat restorers respectively and for reversing the functions of regenerator sets, the combination of vertical ducts arranged in the columnar partitions between the heating flues of each heating wall and opening into said horizontal channel, each cross partition having a pair of such vertical ducts, oblique ascending transfer passages issuing from the regenerators and opening directly into the lower ends of said paired vertical ducts and into the lower ends of said heating flues also, and ports leading out of one side of each heating flue near the bottom and also at one level at least below the top and communicating with both the vertical ducts adjacent to said side of the heating flue; the pairs of vertical ducts of the same heating wall being connected alternately with the regenerator sets underlying the coking chambers on opposite sides of said heating wall, the side ports of alternate heating flues of the same heating wall serving to introduce air and optionally fuel gas also from the heat restoring regenerators into said alternate heating flues at more than one level to produce elongated flames by multistage combustion and the side ports of the intermediate heating flues of said last-named heating wall serving to recirculate the products of combustion within said intermediate heating flues, thereby to elongate the flames thereof by dilution of the burning gases.
16. In a regenerative compound coke oven battery having a series of alternate horizontal coking chambers and heating walls therefor arranged side by side in a row, a single row of regenerators arranged underneath each coking chamber, a single row of vertical heating flues and a horizontal channel interconnecting the upper ends of said heating flues arranged in each heating wall, the number of regenerators in each row being half the number of heating flues in each heating wall, means for admitting air to all and fuel gas to every second regenerator of each row, means for withdrawing waste gas from the regenerators, valve means for operating the regenerator sets underlying alternate coking chambers of the row as heat receivers and as heat restorers respectively and for reversing the functions of regenerator sets, the combination of vertical ducts arranged in the columnar partitions between the heating flues of each heating wall and opening into the said horizontal channel, each cross partition having a pair of such vertical ducts, oblique ascending transfer passages issuing from the regenerators and opening directly into the lower ends of said paired vertical ducts and into the lower ends of said heating flues also, and ports leading out of one side of each heating flue near the bottom and also at one level at least below the top and communicating with both the vertical ducts adjacent to said side of the heating flue; the pairs of vertical ducts of the same heating wall being connected alternately with the regenerator sets underlying the coking chambers on opposite sides of said heating wall, the side ports of alternate heating flues of the same heating wall serving to introduce air and optionally fuel gas also from the heat restoring regenerators into said alternate heating flues at more than one level to produce elongated flames by multistage combustion and the side ports of the intermediate heating flues of said last-named heating wall serving to recirculate the products of combustion within said intermediate heating flues, thereby to elongate the flames thereof by dilution of the burning gases.

WILHELM MUELLER.
